(57) **CLAIM**

The ornamental design for a medical humeral stem, as shown and described.

DESCRIPTION

FIG. 1 is a right side perspective view of the medical humeral stem, having threaded holes, showing my new design;

FIG. 2 is a rear right side elevational view thereof, and the left side being a mirror image;

FIG. 3 is a quarter turn front view thereof;

FIG. 4 is another plan right side view, and the left side being a mirror image; and,

FIG. 5 is another right elevational view thereof, and the left being a mirror image.

The broken lines in the drawings illustrate environmental structure and form no part of the claimed design.
